UNITED STATES PATENT OFFICE.

EDWARD J. SPINK, OF DAVENPORT, IOWA.

EXTENSION-TABLE.

SPECIFICATION forming part of Letters Patent No. 694,439, dated March 4, 1902.

Application filed March 14, 1901. Serial No. 51,125. (No model.)

To all whom it may concern:

Be it known that I, EDWARD J. SPINK, a citizen of the United States, residing at Davenport, in the county of Scott and State of Iowa, have invented a new and useful Extension-Table, of which the following is a specification.

This invention relates to extension-tables, the object in view being to provide an extension-table having, in combination with fixed and movable table-top sections, a flexible slatted-top section which is interposed between the fixed and movable sections and associated with one or more metal guides which engage with the flexible section intermediate the opposite side edges thereof for the purpose of guiding the flexible section as it is folded and rolling the same up into compact shape beneath the plane of the table-top.

One of the principal aims of the present invention is to so combine the flexible section with the guides therefor as to locate the guides between the side edges of the table-top and render it practicable to construct all of the table-top sections of uniform width, thereby doing away with any objectionable offsets or projections which give greater width to certain portions of the table-top than others.

In connection with the several table-top sections and the guiding means for the flexible section it is also an object of the present invention to provide end-supporting legs which have yokes connected to the movable end section and to the extension-slides, so as to establish a firm connection between the central and end portions of the table.

With the above and other objects in view, which will more fully appear as the description proceeds, the invention consists in the novel construction, combination, and arrangement hereinafter set forth, illustrated, and claimed.

In the accompanying drawings, Figure 1 is a perspective view of an extension-table constructed in accordance with the present invention, showing one end thereof drawn outward and the other end folded or moved inward. Fig. 2 is a bottom plan view of a portion of the table. Fig. 3 is a side elevation of a portion of the table, showing one end drawn outward. Fig. 4 is a similar view showing the end section pushed inward. Fig. 5 is a detail perspective view of one of the end-supporting

legs, including the yoke and its brackets. Fig. 6 is a detail perspective view of the guide seat or step. Fig. 7 is an enlarged detail section through a portion of one of the slats of the flexible top section, also showing a curved guide in engagement therewith. Fig. 8 is a detail section on the line 8-8 of Fig. 3.

Similar numerals of reference designate corresponding parts in all figures of the drawings.

The extension-table contemplated in this invention comprises, essentially, the fixed table-top section or central panel 1 and the movable end sections 2, which are adjustable relatively to the center panel or fixed section 1. The fixed section 1 has united to its lower side the parallel guide-bars 3, in connection with which the usual extension-slides 4 are employed, and said extension-slides 4 are connected at their extremities by a cross-bar 5.

The fixed section 1 is supported by means of a center leg 6, connected at its upper end to a frame 7, affixed to the guide-bars 3. The end-supporting legs 8 are provided with the U-shaped yokes or leg-frames 9, having arms of different lengths, to each of which is rigidly secured a flanged metal bracket 10, provided with openings to receive suitable fasteners by means of which the brackets are firmly connected to the movable end section 2 and to a cross-bar 11, connecting the adjacent ends of the extension-slides 4 in the manner illustrated in Figs. 2 and 4. In this way the end sections 2 are rigidly and firmly connected to the extension-slides 4, so as to enable the end sections to be drawn away from the central fixed section or pushed toward the same.

By constructing the yokes 9 in the form illustrated and described provision is made for folding the flexible sections of the table-top upon the guides hereinafter described and within the plane defined by the yokes 9. The flexible table-top section 12 is composed of a series of slats which are preferably tongued and grooved, so as to interlock in the manner illustrated in Figs. 1 and 3, thus keeping the slats in alignment with each other. The slats are all connected together by means of several flexible connecting-strips 13 and 14, arranged, respectively, on opposite sides of the guides hereinafter referred to. The strips

13 and 14 may be of any suitable flexible material, such as textile fabric, and are extended inward far enough to connect firmly with the lower surface of the center panel or fixed section 1, as illustrated in Figs. 2 and 4. The strips 13 and 14 are preferably united to the slats by cement or other suitable adhesive material. The flexible table-top section 12 is provided in its lower side with a plurality of 10 guide-grooves 15, which in cross-section are of T shape or, in other words, provided with the oppositely-extending undercut portions 16, adapted to receive the oppositely-projecting flanges 17 of a U-shaped metal guide-strip 18, one end of which is rigidly held by suitable fasteners 19 in the groove 20, formed in the grooved outer surface of a guide seat or stem 21, which consists of a metal block mortised to the upper edge of the end of 20 cross-bar 5 and held in place by the same fasteners 19 above referred to. It will be understood that one, two, or more of said guides may be employed, and each one of them is curved in involute form, as shown in the several figures of the drawings, so that when the flexible section 12 is folded, as shown in Fig. 4, it will lie within the space between the upwardly-extending arms of the yokes 9 of the end-supporting legs 8 and be protected 25 thereby. The particular form of engagement between the slats of the flexible section and the guides prevents any disengagement between the slats and guides and enables the slats to traverse the guides with ease and very little friction. Furthermore, the particular construction of guides affords a stable and comparatively rigid structure that will not readily collapse or bend. In order to form a close joint between the movable end sections 2 and 30 the flexible section 12, the inner edges of the sections 2 are preferably rabbeted, and cross-strips 22 are set flush in the rabbets and have their inner edges chamfered on the under side, so as to allow the slats of the flexible section to readily slide beneath the same in the act of folding the flexible section. 35

The end sections 2 are provided with the usual end and side rails 23 and 24, respectively, and the center panel is also provided 40 with side-rail sections 25, the extremities of the side-rails sections 24 and 25 being beveled, as shown at 26, to abut against the slats of the flexible section or lie in close proximity thereto when the end sections are pushed inward, as shown in Fig. 4.

From the foregoing description it will be seen that the guides for the flexible table-top section are located at points intermediate the opposite side edges thereof, and by reason of 45 this arrangement in connection with the yokes on the end-supporting legs it is practicable to construct all of the table-top sections of uniform width, thereby doing away with the objectionable feature of having top sections of different widths and unsightly and undesirable projections or offsets, which are easily discernible even when the table is covered

by the usual cloth. The construction described also enables the table to be easily and quickly extended or contracted and does 70 away with the necessity of using detachable leaves such as are now in common use.

Various changes in the form, proportion, and minor details of construction may be resorted to without departing from the principle or sacrificing any of the advantages of the invention. 75

Having thus described the invention, what I claim is—

1. In an extension-table, the combination 80 with a fixed section, of a movable section comprising an end and slides spaced therefrom, said slides having a slidable engagement with the fixed section, a leg supporting the movable section, a yoke having its ends 85 secured respectively to the end of the movable section and the slides leaving an intermediate open space, a guide secured at its upper end to the slides in the space between said slides and the end, and depending below the slides, and a flexible top section supported upon the slides and having a slidable engagement with the guide, whereby said flexible top will be located within the yoke when the movable section is arranged contiguous to the 95 fixed section.

2. In an extension-table, the combination 100 with a fixed section, of a movable section comprising an end and slides spaced therefrom, said slides having a slidable engagement with the fixed section, a leg having a yoke, the ends of which are secured respectively to the end of the movable section and the slides, leaving an intermediate open space, a guide secured at its upper end to the slides 105 contiguous to the space and located below the plane of the top and within the vertical planes of the sides of the yoke, and a flexible top section secured to the edge of the fixed section and having a slidable engagement with 110 the guide, whereby said flexible top will be located within the yoke of the leg when the movable section is arranged contiguous to the fixed section.

3. In an extension-table, the combination 115 with a fixed section, of a movable section comprising an end and slides spaced therefrom, said slides having a slidable engagement with the fixed section, a leg having a yoke, the ends of which are secured respectively to the end of the movable section and the slides leaving an intermediate open space, an involute guide secured at its upper end to the slides contiguous to the space and located below the plane of the top and within the vertical planes of the sides of the yoke, and a flexible top section secured to the edge of the fixed section and having a slidable engagement with the guide, whereby said flexible top will be located within the yoke of the leg 125 120 when the movable section is arranged contiguous to the fixed section.

4. In an extension-table, the combination 130 with a fixed section, of a movable section com-

prising an end and slides spaced therefrom, said slides having a slidable engagement with the fixed section, a leg having a yoke the ends of which are secured respectively to the end 5 and slides of the removable section leaving an intermediate open space, an involute guide secured solely at its upper end to the slides contiguous to the space and depending below the plane of the top and within the vertical 10 planes of the sides of the yoke, and a flexible top section secured to the edge of the fixed section and having a slidable engagement with the guide, whereby the said flexible top will be located within the yoke of the leg 15 when the movable section is arranged contiguous to the fixed section.

5. In an extension-table, the combination with relatively fixed and movable sections, one of said sections comprising an end having 20 a flat top and a slide-frame having a slidable engagement with the other section and spaced from the end member, said end member and slide-frame being connected, a flexible top secured to the other member and normally supported upon the slide-frame, and a guide arranged to receive the flexible top and depending in the space between the end member and the slide-frame, said guide having its upper end located substantially level with the 25 upper edge of and secured to the outer end of the slide-frame, whereby said guide will receive the flexible top immediately upon its movement from the slide-frame.

6. In an extension-table, the combination 30 with a fixed section having a top, of a movable section having a top and a slide-frame spaced from the top and slidably engaging the fixed section, means connecting the top and slide-frame of the movable section to hold them in 35 fixed relation, a curved metallic guide secured at its upper end to the outer end of the slide-frame, and comprising an involute strip substantially U shape in cross-section, and provided with outstanding side flanges, and 40 a flexible top secured at one end to the fixed section and having an undercut groove that receives the flanges of the guide-strip.

7. In an extension-table, the combination 45 with fixed and movable table-sections having 50 rigid tops, of extension-slides slidably engaging the fixed section, a flexible top secured to

the fixed section and arranged to rest upon the slides, a depending guide for the flexible top secured to the slides, supporting-legs provided with curved yokes which embrace the 55 folded flexible top section, the arms of the yokes being of unequal length, and brackets secured to said yokes and fastened respectively to the fixed section and slides.

8. In an extension-table, fixed and movable 60 table-top sections, in combination with an interposed flexible table-top section, extension-slides connected by a cross-bar, a curved guide for the flexible section, and a guide-seat secured to the cross-bar and consisting 65 of a block having a curved surface which is grooved to receive a portion of the guide.

9. In an extension-table, the combination with a fixed section, of a movable section comprising an end and slides spaced therefrom, 70 said slides having a slidable engagement with the fixed section, a connection between the end and slides to maintain their spaced relation, a guide secured at its upper end to the slides and having said upper end located 75 substantially level with the upper edge of the slides and depending beneath the same, and a flexible top supported on the slides and having a sliding engagement with the guide immediately on its movement from the slides. 80

10. In an extension-table, the combination with a fixed section having a flat top, guide-bars secured to the under side thereof, and a leg secured to the center of the guide-bars, of a movable section comprising an end and a 85 slide-frame spaced therefrom and having a sliding connection with the guide-bars of the fixed section, a yoke connecting the end and slide-frame to maintain their spaced relation, a guide secured at its upper end to the slide-frame and depending below the same in the 90 space between the frame and end, and a flexible top secured to one edge of the fixed top and engaging the guide.

In testimony that I claim the foregoing as 95 my own I have hereto affixed my signature in the presence of two witnesses.

EDWARD J. SPINK.
